(57) **CLAIM**

The ornamental design for a display screen of finder of digital camera with transitional graphical user interface, as shown and described.

DESCRIPTION

FIG. 1 is a first image of a display screen of finder of digital camera with transitional graphical user interface showing my new design, with the display screen shown enlarged and removed from the digital camera;

FIG. 2 is a second image thereof;

FIG. 3 is a third image thereof;

FIG. 4 is a front view of the display screen of finder of digital camera with transitional graphical user interface of FIG. 1; FIG. 5 is a rear view thereof;

FIG. 6 is a left side view thereof;

FIG. 7 is a right side view thereof;

FIG. 8 is a top plan view thereof; and,

FIG. 9 is a bottom view thereof.

The portions in broken lines represent the display screen of finder of digital camera and form no part of the claimed design.
